UNITED STATES PATENT OFFICE.

JESSE N. PRINGLE, OF ORTEGA, FLORIDA, ASSIGNOR OF ONE-HALF TO WILL V. STROM, OF JACKSONVILLE, FLORIDA.

SANITARY BOTTLE-MOUTH GUARD.

1,382,318.

Specification of Letters Patent. Patented June 21, 1921.

Application filed March 6, 1920. Serial No. 363,635.

To all whom it may concern:

Be it known that I, JESSE N. PRINGLE, a citizen of the United States, residing at Ortega, in the county of Duval and State 5 of Florida, have invented new and useful Improvements in Sanitary Bottle-Mouth Guards, of which the following is a specification.

The object of my present invention is the 10 provision of an extremely simple, inexpensive and sanitary guard, readily applicable to the mouth of a bottle after the removal of a closure cap therefrom, and adapted to yieldingly retain itself in working position, 15 and to effectively prevent the lips or tongue of a drinker from contacting with the bottle mouth, and this without liability of any of the contents of the bottle getting between the guard and the glass of the bottle mouth. 20 After its use in the manner and for the purpose set forth, my novel guard is adapted to be expeditiously and easily sprung off the usual enlargement on the bottle neck, so as not to add in any measure to the work 25 involved in the thorough cleansing of the bottle.

To the attainment of the foregoing, the invention consists in the improvement as hereinafter described and definitely claimed.

30 In the accompanying drawings, hereby made a part hereof:

Figure 1 is a side elevation showing my novel guard as properly applied to the mouth of a bottle.

35 Fig. 2 is a diametrical section of the same bringing out clearly the flush arrangement of the upper edge of the guard with the inner side of the orifice wall of the bottle.

Fig. 3 is an elevation of my novel guard 40 *per se.*

Fig. 4 is an inverted plan view of the guard *per se.*

Similar numerals of reference designate 45 corresponding parts in all of the views of the drawings.

In Figs. 1 and 2, I show my novel guard as applied to the mouth of a bottle having on its neck 2 an exterior enlargement or hip 3. Such bottles, as is well known, are generally used in the distribution of soft drinks.

50 My novel guard, for the sake of cheapness, is formed of waterproof paper, such as waxed or paraffin paper, and is pressed into the shape shown so that the guard comprises a cylindrical wall 4, a bead 5 at the

lower end thereof, and an inwardly reaching annular flange 6 at the upper end of the cylindrical wall and continuous therewith; the said flange being disposed at approximate right angles so as to rest in opposed 60 relation to the end 7 of the bottle neck, and being of such width that its free edge 8 will rest flush with the inner side 9 of the orifice wall of the mouth.

Manifestly after the closure cap is removed from a bottle, my novel guard may 65 be expeditiously and easily slipped over the mouth, and when the guard is so applied, its bead 5 will hug or spring past the hip or enlargement 3 on the bottle neck, and therefore will serve to yieldingly retain the guard in working position. It is to be understood in this connection, however, that after use, the guard may be readily removed 70 from the bottle mouth by exerting a little 75 endwise outward stress on the guard so as to spring the bead 5 outwardly past the hip or enlargement 3.

In the practical use of my novel guard applied in the manner stated, the lips of the 80 drinker will be applied to the cylindrical wall 4 of the guard, and the tongue of the drinker is applied to the flange 6. It follows from this that both the lips and the tongue of the drinker will be kept from contact with the glass of the bottle, and at the same time, the tongue of the drinker will, by pressing the flange 6 against the end of the bottle neck, preclude the possibility of 85 any of the liquid getting between the guard 90 and the outer side of the bottle neck. From this it follows that incidental to the use of my novel guard, there is no liability of the exterior of the bottle neck being covered 95 with liquid, as when the bottle is set down in upright position after a portion of the contents thereof have been removed.

It will be readily appreciated from the foregoing that notwithstanding its capacity 100 to form a sanitary guard for the mouth of a bottle when a person drinks out of the mouth, my novel guard is extremely simple and inexpensive. In fact the guard is so inexpensive, that it is entirely feasible to throw the guards away after the individual 105 use thereof.

Having described my invention, what I claim and desire to secure by Letters-Patent, is:

As a new and useful article of manufac- 110

ture, a removable sanitary guard for the open mouth of a bottle; the said guard being formed of waterproof paper and including a cylindrical wall, of comparatively large diameter at its lower end, and a thin flexible flange reaching inwardly at substantially right angles from the upper end of the cylindrical wall to be pressed and held by the lips and tongue of a drinker 10 flat against a bottle-neck end and being of

such width that its free edge will rest flush with the inner side of the orifice wall of the bottle neck, whereby said flange is enabled to prevent contact between the bottle-neck end and the tongue of a person and is also 15 enabled to prevent passage of liquid between the bottle and guard.

In testimony whereof I affix my signature.

JESSE N. PRINGLE.
